UNITED STATES PATENT OFFICE.

NATHAN A. ROBERTS, OF PUTNAM, CONNECTICUT.

ROTARY ENGINE.

1,232,845.

Specification of Letters Patent. Patented July 10, 1917.

Application filed April 20, 1916. Serial No. 92,487.

To all whom it may concern:

Be it known that I, NATHAN A. ROBERTS, a citizen of the United States, residing at Putnam, in the county of Windham and 5 State of Connecticut, have invented certain new and useful Improvements in Rotary Engines, of which the following is a specification.

This invention has relation to rotary engines, and the nature and objects thereof will be readily apparent to those skilled in the art to which it appertains, in the light of the following explanation of the accompanying drawings, illustrating what I now believe to be the preferred embodiment, or mechanical expression, of my invention from among other forms and arrangements within the spirit thereof and the scope of the appended claims.

20 However, an object of the invention is to provide an engine of the rotary type in which the inlet and exhaust ports will be of improved form and arranged in such manner in the enlarged or thickened side of 25 the cylinder as to properly direct the motive fluid to the piston of the rotor and equally distribute the fluid throughout the length of the piston for immediate expansion and thereby increase the rapidity of rotation of 30 the rotor and result in a very efficient machine.

Another object of the invention resides in the provision of an efficient rotary engine which will be composed of the minimum 35 number of parts and of simple construction and operation.

In addition to the foregoing, my invention comprehends improvements in the details of construction and arrangement of 40 parts to be hereinafter described and particularly pointed out in the appended claims.

In the accompanying drawings in which similar and corresponding parts are designated by the same characters of reference 45 throughout the several views in which they appear;

Figure 1, is a vertical, longitudinal section through a rotary engine constructed after the manner of my invention.

50 Fig. 2, is a transverse section through the engine illustrating the rotor at the beginning of a working revolution.

Fig. 3, is a view similar to Fig. 2 illustrating a different position of the rotor.

Fig. 4, is a detail view in side elevation of 55 the rotor, and

Fig. 5, is a view in perspective of the piston.

With reference to the drawings, 1 designates the cylinder casing of my engine, 60 mounted upon a base 2, and provided with a longitudinal extending cylindrical bore 3, which is preferably eccentrically disposed so as to provide a relatively wide portion at the upper part of the cylinder for the 65 passage therethrough of fluid ports. Cylinder heads 4, are removably secured to each end of the cylinder by means of bolts 5, each cylinder head having formed upon its inner surface a cylindrical boss or enlargement 6, which is concentrically disposed within the bore and spaced from the inner surface of said bore to form an annular channel 7.

A rotor 8, in the form of a cylinder is eccentrically mounted within the bore of the casing, and is provided with reduced portions 9 at either end, forming shafts which are journaled in openings 10 centrally formed in the cylinder heads 4. The rotor 8, is formed with a transversely extending diametrical recess 11 for the reception of a radially movable piston 12 which is formed at opposite ends with extensions 13 adapted to engage the annular channels 7 and the 85 sides of the bore and the bosses 6. A longitudinal recess 14 is formed at the outer end of the piston for the reception of a packing strip 15 which is normally held in engagement with the inner surface of the bore by 90 means of resilient elements 16.

A radially extending recess 17 is formed at the upper portion of the cylinder and in the inner surface of the bore for the reception of a movable packing strip 18 normally 95 held in engagement with the periphery of the rotor by means of coil springs 19 seated in recesses 20 intersecting the recess 17. Ports 21 are formed in the surface of the bore at each side of the packing strip 18, 100 and extend throughout the length of the bore, and are formed with converging sides 22, leading toward the top of the cylinder for communication with a vertical opening in which supply, or exhaust pipes 23 are 105 connected.

In the operation of this engine steam or other expansible fluid is admitted into one

of the pipes 23, and permitted to expand in the port 21 in communication therewith, from which port the fluid expands into the crescent shaped space within the cylinder 5 formed by the eccentric disposition of the rotor therein. The expansion of the steam within said space and between the packing strip and the piston 12, causes rotation of the rotor, the said piston meanwhile being 10 retained in engagement with the surface of the bore and following the contour thereof during rotation of the rotor by the engagement of the extensions 13 of the piston in the annular channel 7. The expanded steam 15 from a previous working revolution is exhausted into the atmosphere through the port located at the other side of the packing strip, the exhaustion being accelerated by the movement of the piston which decreases the volume of the crescent shaped 20 space at the exhaust side of the engine. It is obvious that the rotation of the rotor may be reversed by admitting the steam into the other port 21, whereupon the first mentioned 25 port performs the functions of an exhaust port. Power may be taken from the engine by means of a pulley (not shown) on one of the shafts 9, and if the machine is to be employed in the capacity of a pump power may 30 be likewise applied to said pulley.

Owing to the diverging shape of the ports, the fluid under pressure may be applied instantly to the piston throughout its length for immediate expansion and thereby increase the rapidity of rotation of the rotor and result in a very efficient machine.

While I have described my invention with some degree of particularity, various ways of reconstructing the same to employ the 40 principles presented therein will occur to those skilled in the mechanical arts, and I therefore reserve the right and privilege of changing the form of the details of construction or otherwise altering the arrangement of the correlated elements without departing from the spirit of the invention, or 45 the scope of the appended claims.

Having thus described my invention what I claim as new and desire to secure by 50 Letters Patent is:—

1. A rotary engine including a cylinder having a longitudinal bore eccentrically disposed to form a thickened portion at one side of the cylinder and exhaust and inlet 55 ports in said thickened portion, cylinder heads having circular enlargements extending concentrically into the bore and spaced from the sides thereof to form annular

channels, a rotor eccentrically mounted in the bore and engaging the cylinder at the thickened portion, a radially movable piston in the rotor and having extensions at each end for engaging in the annular channel, a longitudinal recess provided in the piston, a packing strip in the recess, and a sliding 65 packing strip in the cylinder and between the ports for engaging the surface of the rotor.

2. A rotary engine including a cylinder having a longitudinal bore eccentrically disposed to form a thickened portion at one side of the cylinder, said thickened portion having converging inlet and exhaust ports extended therethrough, cylinder heads having enlargements extending concentrically 75 into the bore and spaced from the sides thereof to form annular channels, a rotor eccentrically mounted in the bore and engaging the cylinder at the thickened portion thereof, a movable piston in the rotor 80 and having extensions engaging in the annular channels, and a packing strip carried by said piston.

3. A rotary engine including a cylinder having a longitudinal bore eccentrically disposed to form a thickened portion at one side of the cylinder, said cylinder having exhaust and inlet ports in said thickened portion, the walls of said exhaust and inlet ports diverging toward their inner ends, a 90 rotor eccentrically mounted in the bore, a piston carried by said rotor and movable diametrically through said rotor, a packing strip carried by said piston, means retaining said packing strip in engagement with the 95 wall of said cylinder during rotation of said rotor, exhaust and inlet pipes connecting with said exhaust and inlet ports, said exhaust and inlet ports having converging sides leading toward the top of the cylinder 100 for communication with the exhaust and inlet pipes, said converging sides of the exhaust and inlet ports causing application of the fluid under pressure to the piston throughout its length for immediate expansion, thereby increasing the rapidity of 105 rotation of the rotor, and a resiliently mounted packing strip carried by said cylinder and bearing upon said rotor.

In testimony whereof I affix my signature 110 in presence of two witnesses.

NATHAN A. ROBERTS.
